UNITED STATES PATENT OFFICE.

HARRY WALLACE JEANNIN, OF WARREN, OHIO.

ALTERNATING-CURRENT MOTOR.

1,322,451.

Specification of Letters Patent.

Patented Nov. 18, 1919.

Application filed January 17, 1917, Serial No. 142,817. Renewed August 25, 1919. Serial No. 319,656.

To all whom it may concern:

Be it known that I, HARRY W. JEANNIN, a citizen of the United States, and a resident of Warren, in the county of Trumbull and State of Ohio, have invented a new and Improved Alternating-Current Motor, of which the following is a full, clear, and exact description.

This invention relates to alternating current motors of that type disclosed in my application for United States Letters Patent, Serial Number 47040, filed August 24, 1915, patented Dec. 19, 1916, No. 1,209,443, wherein brushes bear against the commutator during starting, and after the armature has attained speed the brushes are removed from the commutator and the latter short circuited; or, in other words, the motor is started on the repulsion principle, and after normal speed is attained it operates on the induction principle.

The invention has for its general objects to improve the construction and operation of dynamo electric machines of the character referred to so as to be reliable and efficient in use, comparatively inexpensive to manufacture, and so designed as to have a larger output without increasing the size of the armature.

A more specific object of the invention is to provide a double-wound armature in combination with a commutator of novel construction, and means for short circuiting the armature and removing the brushes, whereby the high resistance winding of the armature is commutated in starting and the low resistance uncommutated winding is short circuited to operate as a squirrel cage induction motor winding after a normal speed is attained; and simultaneously with the short circuiting of the low resistance winding the high resistance winding is short circuited and the brushes moved to open circuit position.

Another object of the invention is to provide an armature having a high resistance starting winding disposed in the usual slots and retained therein by copper bars in place of the usual wooden wedges, such bars being connected at the front of the armature with a commutator, and being connected at the rear by a conducting ring or the like, so that when the commutator segments are

short-circuited a squirrel cage winding is produced.

Still another object of the invention is to provide a duplex commutator in the form of a single unit, one set of segments being connected with the low resistance winding and the other set with the high resistance winding, and both sets being adapted to be short circuited by a common short circuiting ring, and the commutator of the high resistance winding being normally engaged by commutating brushes.

Still another object of the invention is to provide a simple, novel and effective speed responsive device mounted on the armature and operatively connected with the short circuiting ring and the brush throw-out devices, whereby at a certain speed the ring is thrown to short circuiting position and the brushes are thrown out to open circuit position.

The invention has as a further object to provide a simple, novel and effective brush-operating means.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference indicate corresponding parts in all the views,

Figure 1 is a central vertical section of the motor;

Fig. 2 is an enlarged fragmentary sectional view showing the commutator, armature winding connections and brush throw-out device;

Fig. 3 is an enlarged view of the brush throw-out device in the other extreme position from that shown in Fig. 2;

Fig. 4 is a fragmentary face view of the brush-holding means and high resistance winding section of the commutator;

Figs. 5, 6 and 7 are detail sectional views respectively on the lines 5—5, 6—6 and 7—7, Fig. 2;

Fig. 8 is a perspective view of one of the anchoring plates for the segments of the starting commutator;

Fig. 9 is a fragmentary perspective view showing the relation of the two sets of commutator segments;

Fig. 10 is a transverse section on the line 5:10—10 Fig. 1, showing the speed responsive device;

Fig. 11 is a similar view showing the weights thrown outwardly from their normal position shown in Fig. 10; and

10 Fig. 12 is a longitudinal sectional view showing the parts of the speed responsive device.

Referring to the drawing, 1 designates the frame of the motor, 2 the stator or field element therein, 3 the rotor or armature element mounted on a shaft 4 that is journaled in bearings 5, 6 the commutator, 7 the brush-holding and operating means, 8 the speed responsive device, 9 the commutator short circuiting device, and 10 the sleeve connected with the speed responsive device and operatively related to the brushes and a short circuiting ring to throw out the brushes simultaneously with the moving of the short circuiting ring to position to short circuit the segments of the commutator.

The frame and stator may be of any approved construction. The rotor or armature 3 is provided with a high resistance winding 11, the coils of which are set in slots 12 of the armature, as shown in Figs. 1 and 7, and this winding is employed for starting the motor on the repulsion principle by means of the commutator and brushes.

35 The armature slots 12 are closed by bars of copper 13 which take the place of the wooden wedges usually employed for holding in the windings, and these copper bars are connected together electrically by a ring 40 14^{1/2} on the rear of the armature, and the front ends of the bars are connected with commutator segments which, when grounded, cause the bars to form a squirrel cage winding, which is in service after the motor has 45 started, and operates on the induction principle. This low resistance winding formed by the bars is uncommutated, as no brushes are employed in connection therewith, and the bars are in service only after the armature 50 has attained speed and the said bars are short circuited by the use of the short circuiting ring 9.

Since the armature is of the double-wound type, a special form of commutator is employed for enabling the high resistance winding to be employed in starting, while the low resistance winding is idle, and to enable both windings to be short circuited when the motor is normally operating. The 60 commutator comprises two sets of bars 14 and 15 radially disposed about the shaft, and the set 15 is disposed behind the set 14. The set of commutator bars 15 is shown with dovetailed recesses 16, whereby these 65 bars can be effectively anchored in an an-

nular body 17 of bakelite or equivalent insulating material which is molded on a metallic ring 18 screwed on the hub 19 of the armature. The commutator bars 14 are also anchored in the insulation 17 by means of anchor plates 20 constructed as shown in Fig. 8. These are thin plates of copper, one for each bar 14, to the side of which it is soldered. The anchoring plates 20 pass between the rear set of commutator bars 15 and are separated therefrom by strips of insulation 21, as shown in Fig. 6, and the rear edges of the plates 20 have apertured lugs 22 which are embedded in the insulation body 17. The outer end of the bars 14 have recesses 23, as shown in Figs. 4 and 5, and in these recesses are soldered terminals 24 of the coils of the high resistance winding 11. The outer ends of the rear set of commutator bars 15 have metal connectors 25, which, as shown in Fig. 5, are set in slots 26 of the bars 15 and have their outer ends bent around the forward ends of the copper conductors 13, there being one commutator bar 15 for each conductor 13. The inner ends of the commutator bars 15 project inwardly beyond the inner ends of the bars 14, and the plates 20 have inwardly projecting ears 27. These ears 27 have beveled surfaces 28, while the commutator bars 15 have beveled surfaces 29 which register with the beveled surfaces 28, so that the short-circuiting device or ring 9 can bear on these beveled surfaces of the bars 15 and plates 20 to thereby short circuit both sets of commutator bars 14 and 15 when the ring 9 is in the position shown in Fig. 1.

The brush holders 7 are mounted on a ring 30 fastened to the left bearing housing 31, Fig. 1, and each holder comprises a radially extending arm 32 on the ring 30 and a Z-shaped plate 33 fastened to the ring 30 in such relation to the arm 32 as to constitute a box or guide in which is slidably mounted a brush 34 which has a movement parallel with the axis of the motor shaft or at right-angles to the face of the commutator. These brushes are adapted to bear on the bars or segments 14 of the commutator when the motor starts, whereby the high resistance winding will be commutated, and when the motor has attained speed, the brushes are automatically withdrawn out of engagement with the commutator. Each brush has fastened to one side a plate 35 which has a recess 36 into which engages a lug 37 on a lever 38. This lever is fastened to a pivot pin 39 journaled in bearing lugs 40 on the brush housing or box, and a torsional spring 41 surrounding the pivot pin 39 acts on the arm 38 to move the latter toward the right, Figs. 1, 2 and 3. In other words, the brush is urged into engagement with the commutator and yielding contact is maintained therewith by the spring 41. On each 130

brush housing is fulcrumed at 42 a lever 43 provided with an outwardly extending arm 44 which has a lug 45 that engages the associated lever 38, and on the elbow portion 46 of the lever 43 is a roller 47 which is adapted to be engaged by an axially movable ring or collar 48 surrounding the armature shaft and operatively connected with the speed responsive device 8. Under 10 starting conditions the brush throw-out ring 48 is in the position shown in Fig. 2 and out of contact with the rollers 47. In other words, the springs 41 of the brushes hold the levers 43 inwardly, and the brushes are 15 maintained in contact with the commutator. When the motor attains speed, the throw-out element 48 moves from the position shown in Fig. 2 to that shown in Figs. 1 and 3, and consequently the levers 43 are 20 thrown outwardly, and they in turn operate on the levers 38 so as to move the brushes forwardly out of contact with the commutator. When the motor stops, the ring 48 returns to the position shown in Fig. 2, and the 25 brushes reengage the commutator. The brush throw-out ring 48 is connected with the reciprocating sleeve 10 on which is mounted the short-circuiting device 9, so that when the short circuiting device comes 30 into play to short circuit the commutator, the brushes 34 will simultaneously be thrown out of engagement with the commutator.

The speed responsive device 8 comprises a pair of swinging weights 50 arranged with 35 in a cylindrical hub extension 51 on the rear of the armature. These weights are pivotally mounted at 52 on opposite sides of the armature shaft to swing in a plane transverse to the latter from the position 40 shown in Fig. 10 to that shown in Fig. 11, or vice versa. Each weight acts on a bell-crank lever 53 that is connected by links 54 in a manner disclosed in the patent heretofore referred to, with the sleeve 10. The 45 bell-crank levers are fulcrumed on pins 55 mounted in the hub of the armature, and each lever has an arm 56 which bears against its associated weight 50 near the pivoted end thereof, as clearly shown in Figs. 10 and 11. The bell-crank levers are maintained in contact 50 with their associated weights by reason of the tension of the spring 10° which operates on the sleeve 10 to move the same to the left, Fig. 1. This spring exerts a pull 55 on the links 54, which in turn hold the bell-crank levers 53 against the weights no matter in what position the latter may be. As the weights move inwardly or outwardly the bell-crank levers have a wiping engagement therewith, and to minimize friction the levers have rounded extremities which engage the weights. Normally the weights are in the position shown in Fig. 10, which corresponds to the position of the parts shown 60 in Fig. 2. When the motor attains speed 65

the weights are thrown outwardly and these in turn operate through the levers 53, links 54 and sleeve 10, to move the short-circuiting device 9 into engagement with the commutator and the throw-out ring 48 into engagement with the levers 43, whereby the brushes are withdrawn from the commutator. 70

From the foregoing description taken in connection with the accompanying drawings, the advantages of the construction and 75 method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall 80 within the scope of the appended claims. 85

Having thus described my invention, I claim as new and desire to secure by Letters Patent:

1. A motor of the class described comprising an armature having high and low 90 resistance windings for starting and running conditions respectively, separate sets of commutator bars connected with the respective windings, brushes bearing on the set of commutator bars connected with the high 95 resistance winding, means for throwing the brushes into and out of operative position, and means for short circuiting both sets of commutator bars under running conditions. 100

2. A motor of the class described comprising an armature having high and low 105 resistance windings for starting and running conditions respectively, separate sets of commutator bars connected with the respective windings, brushes bearing on the set of commutator bars connected with the high resistance winding, means for throwing the brushes into and out of operative position, a short circuiting device for both sets of commutator bars, and a speed responsive 110 means for throwing the short circuiting device into short circuiting position and simultaneously removing the brushes from the commutator. 115

3. A motor including an armature having starting and running windings, a commutator having separate sets of bars, a common bed of insulation in which the bars are mounted, brushes normally bearing on one of the sets of bars, and a short circuiting 120 device normally out of engagement with both sets of bars and movable into engagement therewith and forming means whereby the brushes are removed from the commutator. 125

4. In a motor, an armature having slots, a high resistance starting winding in the slots, copper rods disposed in and closing the slots for retaining the windings therein, separate sets of commutator bars for the winding and rods, brushes adapted to bear 130

on the set of bars connected with the winding, and a short-circuiting device adapted to short circuit both sets of commutator bars and forming means for moving the brushes 5 to open circuit position.

5. In a motor, an armature having slots, a high resistance winding comprising coils mounted in the slots, a commutator connected with the winding, copper rods disposed 10 in the slots for retaining the coils therein, bars to which the rods are connected, means movable into engagement with the said bars for short-circuiting the rods to constitute a low resistance running winding, and brushes 15 engageable with the commutator for employing the high resistance winding for starting.

6. A motor including an armature having high resistance starting and low resistance running windings, separate sets of commutator bars for the windings, anchoring plates connected with one set of bars and extending between and insulated from the other set, a bed of insulation in which the plates are anchored and also the bars between which 25 the plates extend are anchored, brushes adapted to bear on the bars attached to the plates, and a short circuiting device adapted to engage the other set of bars and also the plates, whereby both sets of commutator 30 bars can be short circuited.

7. A commutator for a double-wound armature comprising two sets of commutator bars arranged one behind the other, and the bars of each set being radially disposed, 35 whereby the front set of bars is adapted to be engaged by brushes, and means disposed toward the center of the bars to short-circuit both sets.

8. A commutator for a double-wound 40 armature comprising two sets of radially disposed bars arranged one behind the other, an anchor plate fastened to each bar of the front set and extending rearwardly between the bars of the rear set, and a common bed 45 of insulation in which the rear set and the plates are anchored.

9. A commutator for a double-wound armature comprising two sets of radially disposed bars arranged one behind the other, 50 an anchor plate fastened to each bar of the front set and extending rearwardly between the bars of the rear set, and a common bed of insulation in which the rear set and the plates are anchored, said anchor plates having exposed portions alining with portions 55 of the bars of the rear set for engagement by a short circuiting device.

10. A commutator for a double-wound armature, comprising a front set of radially disposed commutator bars insulated from each other, a rear set of radially disposed commutator bars insulated from each other and from the front set, the rear set having their inner ends extending inwardly beyond the inner ends of the front set, an anchoring plate connecting with each front bar and extending rearwardly between the rear bars and having portions extending inwardly and flush with the inner portions of the rear bars, whereby a short circuiting device 70 can engage said plates and rear bars, and an insulating means in which the rear bars and plates are mounted.

11. A commutator for a double-wound armature, comprising two sets of commutator bars radially disposed, with the outer ends of the front set projecting beyond the outer ends of the rear set, the outer ends of the front set being slotted for connection with the armature coils, and connectors on 80 the outer ends of the rear set for connection with armature conductors.

12. In a motor, the combination of a commutator, brushes adapted to engage the same, holding means for the brushes, levers mounted on the holding means and connected with the brushes, springs operating on the levers to hold the brushes in engagement with the commutator, additional levers mounted on the brush-holding means and each having an outwardly extending arm engageable with one of the aforesaid levers and having an inwardly extending portion provided with a roller, an axially movable element engageable with the rollers of the 95 levers to simultaneously move the same outwardly when the element moves in one direction, said rollers being moved inwardly by the springs when the element moves in the opposite direction, and a speed responsive device for actuating the element.

13. In a motor of the class described, the combination of a commutator, brushes bearing thereon, spring-pressed levers connected with the brushes for yieldingly holding the same against the commutator, levers fulcrumed adjacent the first-mentioned levers for actuating the same against the tension of the springs thereof, and an axially movable element having a wiping single point 105 engagement with the second-mentioned levers for moving the same.

HARRY WALLACE JEANNIN.
